US0D1076104S

(12) **United States Design Patent** (10) **Patent No.:** **US D1,076,104 S**
(45) **Date of Patent:** **** May 20, 2025**

(54) **ORTHOTIC DEVICE**

(71) Applicant: **DENNEROLL HOLDINGS PTY LTD**, Cromer (AU)

(72) Inventor: **Adrian Dennewald**, Waverton (AU)

(73) Assignee: **DENNEROLL HOLDINGS PTY LTD**, Cromer (AU)

(**) Term: **15 Years**

(21) Appl. No.: **29/705,244**

(22) Filed: **Sep. 10, 2019**

Related U.S. Application Data

(60) Continuation of application No. 16/107,840, filed on Aug. 21, 2018, now Pat. No. 11,419,440, and a continuation of application No. 14/865,730, filed on Sep. 25, 2015, now Pat. No. 10,758,069, said application No. 16/107,840 is a division of application No. 14/865,730, filed on Sep. 25, 2015, now Pat. No. 10,758,069, and a continuation-in-part of application No. 29/540,145, filed on Sep. 21, 2015, now Pat. No. Des. 859,664, and a continuation-in-part of application No. 29/539,934, filed on Sep. 18, 2015, now Pat. No. Des. 860,463, said application No. 29/540,145 is a continuation-in-part of application No. 12/468,547, filed on May 19, 2009, now Pat. No. 9,186,004, said application No. 29/539,934 is a continuation of application No. 12/468,547, filed on May 19, 2009, now Pat. No. 9,186,004, said application No. 14/865,730 is a continuation of application No. 12/468,547, filed on May 19, 2009, now Pat. No. 9,186,004, which is a division of application No. 11/524,560, filed on Sep. 21, 2006, now abandoned.
